UNITED STATES PATENT OFFICE.

EMANUEL M. SELL, OF INDEPENDENCE, KANSAS.

BARREL-RACK.

1,313,340.

Specification of Letters Patent.

Patented Aug. 19, 1919.

Application filed May 12, 1919. Serial No. 296,513.

To all whom it may concern:

Be it known that I, EMANUEL M. SELL, a citizen of the United States, residing at Independence, in the county of Montgomery and State of Kansas, have invented certain new and useful Improvements in Barrel-Racks, of which the following is a specification, reference being had to the accompanying drawings.

10 This invention relates to supporting racks, particularly adapted for supporting barrels and like articles.

An object of the invention is the provision of a frame, adapted to rest upon the ground 15 and provided with opposite side uprights, between which a tilting frame is fulcrumed, whereby a barrel may be conveniently supported, and owing to the tilting action of the fulcrumed frame, the barrel is likewise 20 tilted, whereby access is allowed to the contents of the barrel.

A further object of the invention is the provision of means for supporting a barrel 25 in the tilting frame, whereby not only the barrel can be tilted, in order to permit of convenient access to its contents, but also to permit the barrel to be easily and quickly removed from the tiltable frame, when it is necessary to arrange another barrel in 30 position.

A further object of the invention is the provision of bracing members for the lower corners of the tiltable frame.

While the design and construction at 35 present illustrated and set forth is deemed preferable, it is obvious that as a result of a reduction of the invention to a more practical form for commercial purposes, the invention may be susceptible to changes, and 40 the right to these changes is claimed, provided they are comprehended within the scope of what is claimed.

The invention comprises further features 45 and combination of parts, as will be herein-after set forth, shown in the drawings and claimed.

Figure 1 is a view in perspective of an improved barrel rack constructed in accordance with the invention, showing in dotted lines 50 the tiltable frame as having been tilted;

Fig. 2 is a plan view of the same; and

Fig. 3 is an enlarged detail view in elevation of the lower part of the swinging frame, showing parts thereof and the strips 55 18 in section.

Fig. 4 is a detail view of a portion of one

of the sides of the base frame, showing the mounting and one of the uprights 5 and one of the braces 6, showing the connections of the parts.

Referring to the drawings 1 designates a base frame, which may be any suitable shape, preferably rectangular in form, comprising side and end pieces 2 and 3. Secured by suitable bolts or the like 4 to the outer faces of the side pieces 2 are uprights 5, and these uprights are braced or reinforced by means of the braces 6. The lower ends of the braces 6 engage or rest upon the upper edges of the side pieces 2 of the base frame 1, there being wooden pins 7 engaging between the braces 6 and the upper parts of the side pieces 2 of the base or ground frame. Each brace 6 is disposed adjacent the inner face of the upright 5, there being a single bolt 8 passing through the brace 6 and the upright, thereby insuring rigidity and strength.

Suitable bolts engage through the upper portions of the uprights and the braces 5 and 6, and upon the bolts 9, a tiltable frame 10 is mounted. This tiltable frame comprises the vertical side pieces 11 and the upper and lower end pieces 12 and 13, which are braced at the corners of the tiltable frame 85 by means of the angle plates 14, which are secured in position by means of the bolts 15.

Secured by suitable bolts 16 to the bottom piece 13 is a plurality of supporting strips 18. A single bolt passes through each of the supporting strips 18, and through the bottom piece 13. The heads of the bolts 16 are countersunk into the strips 18, sufficiently to permit their outer faces to be flush with the upper faces of the strips 18. It is to be noted that the strips 18 are cut in lengths, and are so arranged as to permit the strips to form a supporting bottom for the barrel. Also it is to be noted that this bottom is capable of engaging the head of the barrel, in order to support the barrel evenly and in a perpendicular position. Furthermore, it is to be observed that the opposite ends of the strips of the bottom terminate in close positions to the chines of the barrel, thereby preventing the lower end of the barrel from displacement relative to the bottom of the tiltable frame.

A semi-circular band 19 is provided, and has its ends secured by bolts 20 to the vertical side pieces 11 of the tiltable frame. This semi-circular band is positioned relatively to the

upper part of the tiltable frame, so that the upper part of the barrel may be engaged therewith, to prevent movement of the barrel in one direction relatively to the tiltable frame. Hooks 21 are pivotally mounted at 22 on the vertical side pieces of the tiltable frame, and are designed to overlie and engage the chines of the upper end of the barrel, to insure holding the barrel in position. An eye 23 is carried by one of the side pieces of the tiltable frame, and connected to the eye is a chain 24, which is designed to pass about the upper part of the barrel 25, and has its other end connected to a hook 26 to the opposite vertical side piece of the tiltable frame. This chain, it will be noted, co-operates with the semi-circular band, in order to insure supporting the barrel firmly on the tiltable frame. Spacing members 27 are interposed between the vertical side pieces of the tiltable frame, and the end pieces of the braces 6 of the uprights 5. These spacing members are carried by the fulcrumed bolts of the tiltable frame, and by means of the spacing members lateral movement of the tiltable frame, to any great degree, is prevented, that is relatively to the braces 6. It will be noted, that the barrel is so supported on the bottom of the tiltable frame, that when said frame is in a vertical position, the barrel will rest on a cross piece 2 at one end of the base or ground frame. When the tiltable frame is tilted, as shown in dotted lines in Fig. 1, it will be observed that the side of the barrel rests upon a cross piece 3 at the opposite end of the ground or base frame, thereby limiting the tiltable frame in its tilting movement. The invention having been set forth what is claimed as new and useful is:

1. In a barrel rack, the combination with a ground frame having cross-pieces at its opposite ends connecting the sides of the ground frame and provided with uprights rising from the opposite side pieces, of a tiltable frame fulcrumed on and between the uprights, and adapted to support a barrel, the opposite sides of the tiltable frame having means to hold the upper end of the barrel in place from tilting relatively to the tiltable frame, the bottom of the tiltable frame having means conforming to and en-

gaging the head of the barrel and fitting within the chines of the barrel, thereby preventing lateral movement of the barrel relatively to the tiltable frame, and whereby as the tiltable frame is disposed vertically one end edge of the barrel may rest upon one of the cross-pieces, and when the tiltable frame is tilted, the side of the barrel may rest upon the other cross-piece. 55 60

2. The combination with a ground or base frame having uprights on its opposite side pieces, of a tiltable frame fulcrumed between and on the uprights, said tiltable frame comprising upper and lower end pieces, angle braces for the corners of the tiltable frame, rigidly bracing the upper and lower end pieces, a barrel supporting bottom on the lower end piece of the tiltable frame, said barrel supporting bottom comprising a plurality of strips secured to the bottom piece of the tiltable frame, the barrel supporting bottom being of a shape to 70 75 fit within the chines of the barrel and conforming to and engaging the head of the barrel, thereby preventing lateral movement of the lower end of the barrel relatively to the tiltable frame, and means co-operating with the upper part of the barrel to hold it in position on the tiltable frame. 80

3. The combination with a base or ground frame, of uprights secured to the outer faces of the side pieces of the base frame, braces 85 rising upwardly from the upper edges of the side pieces of the base frame, means for securing the braces to the inner faces of the uprights, fulcrum bolts extending through the uprights and the braces, a tiltable frame 90 fulcrumed on the bolts, the lower end of the tiltable frame having barrel supporting means so constructed and arranged in co-operation with the lower head of the barrel, as to prevent lateral movement of the barrel 95 relatively to the lower end of the tiltable frame, and means co-operating with the upper part of the barrel to hold the same in position relatively to the tiltable frame.

In testimony whereof I hereunto affix my 100 signature in the presence of two witnesses.

EMANUEL M. SELL.
